WILLIAM FFORD SERVICE, OF NEW BRITAIN, CONNECTICUT.

PLATING MACHINE.

Application filed May 2, 1925. Serial No. 27,339.

My invention relates to improvements in plating machines, of the form that comprises the combination of a conveyor structure for carrying the work and a set of vats or tanks for cleansing water and solutions for cleaning and the actual plating, and, also, having means for delivering the goods from the conveyor, and the object of my improvement is to produce a plating machine that except for the detail of applying the goods to be plated to the conveyor, which latter is done by hand, is essentially automatic; is continuous in its operation; is relatively of moderate dimensions; is simple and economical; and is convenient and efficient.

In the accompanying drawing:—

Figure 1 is a plan view of my improved plating machine, part of the conveyor structure with the work supporting devices being broken away.

Figure 2 is a front elevation of the same. Figure 3 is an end elevation of the same.

Figure 4 is an end elevation as viewed from the other end. Figure 5 is an end face view on an enlarged scale of one of the elevating guide wheels, the cooperating idler wheels being indicated by broken lines.

Figure 6 is a side elevation or edge view of the same in the position for use, with the supporting bracket and adjacent parts.

My improved plating machine comprises in combination a conveyor structure that has the actual conveyor element 10 in the form of an endless cable and a set of vats or tanks. The latter comprise the initial cleaner tank 11; the cyanid tank 12; the water tank 13; the plating tank 14; and the final water tank 15 and the work is carried successively along by the cable 10 and immersed in the water or solutions in the different tanks and in the order named, the different functions performed in the tanks being ordinary. Thus the solution in the initial cleaner tank 11 may be electrically charged through the medium of terminal plates 16 that are immersed in the solution that is provided for cleaning.

The plating tank 14 is provided with anode plates 17.

The conveyor cable 10 serves as the mechanical support for the work to be plated and also as the cathode and to this end is made of a combination of strands of steel and copper.

For supporting the work the cable 10 is

provided with a series of buttons 18 that are made in two parts for being applied to the cable and have a circumferential groove 19 for loosely receiving the eye portion 20 of a hanger 21 of wire. The lower end of the hanger 21 is in the form of an eye 22 and on the latter is hung the hook-shaped upper end 23 of the work hanger or supporting rod 24, the latter being provided with the usual laterally directed branches 25 that are distributed along the length on two opposite sides for receiving the work.

The hooks 23 on the rods 24 are adapted to cooperate with a stripper 26 of wire or the like for removing the work supporting rods 24 from the hangers 21 individually at the delivery end 27 of the machine.

As regards the stripping, this is effected in conjunction with the particular elevator 75 guide wheel 28 that serves to guide and elevate the cable 10 between the final water tank 15 and the initial cleaner tank 11 and which has a set of recesses 29 that open inwardly from the periphery. The wheel 28 has a central peripheral groove 30 for the cable 10 and, under conditions of use, as the cable 10 travels upwardly coincident with the rotation of the wheel the wire hanger 21 falls into one of the recesses 29 so that the eye 22 at the free end overhangs the adjacent outer end face 31 of the wheel 28, said eye being the support for the hook 23, as described. As the hanger 21 descends from the high point of its travel the hook 23 is 90 brought into registration with the free end 32 of the stripper 26 and as the movement of the wheel 28 is continued the rod 24 is finally stripped from the hanger 21 and carried by gravity along the stripper 26, the latter being suitably inclined for the purpose and also being bent to deliver the work to a convenient delivery or receiving point.

An elevator guide wheel 28 is provided at every change from one tank to another and in each case the hangers 21 enter recesses 29 and the rods 24 overhang the wheel and are opposed to the adjacent face 31 of the wheel in the manner described. In order to provide clearance for the work on the rods 24 I 105 provide as an operative support for the same stub shaft 33 or the like that is inclined appreciably from the horizontal so that the wheel will rotate in a plane that is inclined from the vertical. An inclination of about fifteen degrees I find to be sufficient generally. By this provision, the rod 24 with the

work will hang freely and clear of adjacent parts.

The stub shaft 33 is operatively supported by means of a bracket 34 and means are provided in some cases for an appreciable adjustment in elevation, such adjustment being provided to effect clearance of the lower ends of the work supporting rods 24 relatively to the top edges of the adjacent tanks.

10 A pair of idlers 35 cooperate with each of the elevator guide wheels 28 for guiding the cable 10.

The driving wheel 36 is in the form of a grooved pulley that is located adjacent the inner end and at the middle of the width of the plating tank 14; is supported by a vertical shaft 37; and which latter is driven by means of a motor 38. From the two sides of the drive wheel 36 two parallel runs 39 of the cable 10 extend outwardly to two guide wheels 40 adjacent the outer end 41 of the tank 14. From the outer sides of the end guide wheels 40 two runs 42 of the cable 10 travel inwardly adjacent the front side 43 and the rear side 44 respectively of the tank 14 and which runs 42 terminate at the elevator structures 45, each of which has a guide wheel 28 such as has been described.

15 The elevator structures 45 serve simply to 30 elevate the cable 10 with its load, without other change in direction, and may be designated as straightaway elevator structures and in distinction from the return-bend elevator structures 46, of which three are provided so as to provide for both elevation and a reversal in the direction of the cable 10.

20 Consideration will now be given to the location of the different tanks and the movement of the cable under conditions of use.

25 The plating tank 14 is of extra width and each of the other tanks, which may be designated as auxiliary tanks, is substantially one-fourth of the width of the said plating tank, and the four are located side by side 45 and as a whole positioned at the end of the plating tank, with the ends in abutment with the end of the plating tank. Furthermore, the end or finishing tank is the front tank 15 at the left of the plating tank 14 in 50 Fig. 1.

Then in order from front to rear are the initial cleaner tank 11 the cynid tank 12, and the water tank 13.

55 The work travels back and forth four times in the plating tank 14 on the four different runs therein, the final run being designated as 42 adjacent the front wall 43. This last run travels from right to left, over the elevator structure 45, and then along the 60 right to left run 47 in the front finishing water tank 15 to the first return-bend elevator structure 46. Then comes the left to right run 48 in the cleaner tank 11 to the second return-bend elevator structure 46 and 65 from the latter the right to left run 49 in the

cyanid tank 12 to the third return-bend elevator structure 46. From the latter extends the left to right run 50 up to the straightaway elevator structure 45 where it meets the rear run 42 in the plating tank 14. 70

Agitation means for facilitating the plating are provided involving in one case the use of the work and its supporting rods and in another phase the use of a circulating pump 51.

75 The pump 51 may be conveniently located adjacent the front and outer corner 52 of the plating tank 14; has an intake 53 that is located only slightly below the top level 54 of the electrolyte; that has a discharge system through a header 55 that has a plurality of outlets 56 that are distributed around the inner wall of the tank 14, and; which outlets are at a slightly higher elevation than the top level 54 mentioned of the electrolyte. 80

85 The mechanical agitation means, involving the work and work supporting devices, comprises a set of boards 57 that are positioned in the plating tank 14 so that the edge 58 of each is substantially just below the 90 run, 39 or 42 in each case, and so that the hangers 21 would tend to assume a position alongside said edge 58. On said edge, however, are mounted a series of flat springs 59 that are in the path of the hangers and operate to resiliently push the hangers with the work rod 24 to one side. After traveling the length of the spring 59 the hanger 21 slips off from the free end 60 of the spring, resulting in a lateral whipping effect that 95 operates as a positive means of agitation of the liquid.

100 The structure described is relatively compact and efficient and except for applying the work by hand is automatic in operation. 105

I claim as my invention:

1. In a plating machine, a plating tank, a conveyor for supporting work and having a portion that cooperates with said tank, supporting and guide devices for said portion, and said devices being distributed relatively to said portion so as to provide a plurality of return bends therein.

110 2. In a plating machine, a plating tank, means for supporting work for being plated therein, and said means being constructed and arranged to provide a plurality of return bends for effecting a plurality of movements of said work in a given direction while such plating is being effected.

115 3. In a plating machine, a plating tank, a cable cooperating therewith as a conveyor for supporting work, and said cable operating as the electrical conductor for delivering current to said work under operating conditions.

120 4. In a plating machine, a plating tank having an end wall, a conveyor cooperating with said tank, work supporting hangers pivoted individually to said conveyor and 125

130

- having pendant relation thereto when in registration with said tank, supporting and guide devices for said conveyor, and said devices being constructed and arranged to
- 5 provide different elevations for the portions that are in registration respectively with the body of said tank and with said end wall.
5. In a plating machine, a tank having an end wall, a conveyor for supporting work
- 10 and extending over said tank and wall, an elevator guide wheel for said conveyor mounted on said wall, work supports connected to said conveyor and overhanging one face of said wheel, and the operating
- 15 plane of said wheel being inclined from the vertical to provide clearance for said supports relatively to said face.
6. In a plating machine, a plating tank, a conveyor extending over said tank, pendant work holders connected to said conveyor and extending into said tank, and a set of springs positioned below said conveyor, said springs comprising individually a piece of strip material, one end thereof being fixedly supported, the body portion thereof being projected across the path of said work holders under operative conditions, and being of such length as to permit said work holders to slide along said body portion and slip over the free end.
- 20 7. In a plating machine, a conveyor, supporting and guide devices for said conveyor and comprising an elevator guide wheel for elevating said conveyor and involving an
- 25 upward movement of the conveyor on one side and a downward movement on the other side, a hanger connected by one end to said conveyor, having a body portion for extending over the periphery of said wheel, and
- 30 having an eye at the free end, a work supporting rod having a hook for engagement
- with said eye, and a stripping rail structure located in the path of said hook for engaging therewith and stripping the same from such engagement with the eye.
- 45 8. In a plating machine as described in claim 7, said periphery of the wheel being provided with a set of transverse slots for selectively receiving said body portion of the
- 50 hanger.
9. In a plating machine, a set of tanks and a conveyor serving simultaneously as the means for carrying the work to be operated upon in said tanks and as a main conductor for conducting the electrical current for use in effecting the plating of said work.
- 55 10. In a plating machine, a set of tanks arranged successively with edges adjacent, a conveyor with pendant hangers for work and traveling over said tanks, elevator guide wheels for changing the elevation of said conveyor and work over the said edges, and the axes of said guide wheels being inclined to provide for clearance for said work relatively to the opposed faces of said guide wheels.
- 60 11. In a plating machine, a set of tanks, a conveyor with pendant hangers for work and traveling over said tanks, an elevator guide wheel for elevating said conveyor and hangers, and a stripper cooperating with said guide wheel for removing the work from said hangers.
- 65 12. In a plating machine, a conveyor for carrying work in the form of a cable, hangers for supporting said work, grooved pulley devices having plain grooves for guiding said cable, and buttons connecting said hangers with said cable and mounted on said cable for traveling in said grooves.
